UNITED STATES PATENT OFFICE

2,451,424

ENDLESS-TYPE CONVEYER FOR COAL AND
THE LIKE

Ernest Williams, Edwight, W. Va.

Application October 10, 1945, Serial No. 621,556

3 Claims. (Cl. 198—168)

1

The present invention relates to so-called underground conveyors of the endless type such as are expressly adapted for use in the handling of coal in mines, and the primary purpose of the invention is to provide an improved load pushing and scraper flight to be carried by the endless chain.

In conveyor structures of the type under consideration, the frame structure is characterized by so-called delivery and return pans. These are sometimes referred to in the trade as troughs, the coal to be loaded being dumped into the delivery trough and the lower run of the chain and the attached flights traversing back through the return trough. There is presently in use a one-piece scraper unit which has its central portion fashioned into a sort of a chair and this is seated on and fastened to the centrally arranged endless chain, the end portions being formed into properly shaped and inclined scraping blades and these having wiping or scraping contact with the partitions defining the aforementioned upper and lower troughs.

It is well known in this line of endeavor that some of the coal at the discharge end, where the conveyor loads same into cars or trucks, finds its way back in the return trough. Hence, the scraper units or blades simply drag the coal back and it gradually piles up at the intake end and interferes not only with the operation of the machine, but promotes other difficulties. It follows that the principal object of the present invention is to fashion the blades of the respective scraper units with depressions, said depressions forming pocket-like scoops. These scoops, when they reach the pile at the intake end, automatically load themselves, carrying a small portion of the material from said pile back into the delivery trough at the top.

Stated otherwise, the purpose of the present invention is to improve upon what may be referred to as an already marketed type chain scraper unit by simply providing scooping and retrieving pockets in the blade portions thereof.

Other objects, features and advantages will become more readily apparent from the following description and the accompanying illustrative drawings.

In the drawings, wherein like numerals are employed to designate like parts throughout the same:

Figure 1 is a longitudinal view in section and elevation showing the trough or pan construction, the endless conveyor chain, and the improved scraper blade units carried by said chain.

2

Figure 2 is a fragmentary top plan view of the lefthand end of the assemblage seen in Figure 1.

Figure 3 is a central vertical cross-section on the plane of the line 3—3 of Figure 2, looking in the direction of the arrows.

Figure 4 is an enlarged elevational view of one of the scraping blade units, this showing the scooping and retrieving pockets in the blade portions.

10 Figure 5 is a top plan view of the unit shown in Figure 4.

Figure 6 is an end elevation looking from either end of the unit seen in Figures 4 and 5.

Figures 7 and 8 are sections on the planes of 15 the lines 1—1 and 8—8 of Figure 4, looking in the direction of the arrows.

Referring now to the drawings by distinguishing reference numerals, it will be seen that the conveyor, as a unitary structural assemblage, is 20 denoted by the reference numeral 10. The main parts of this assemblage are old and well-known in that said structure includes a generally horizontal, longitudinally extending partition 11 defining the upper load-receiving and delivery 25 trough, this partition being above an underlying generally horizontal, longitudinally extending similar partition 12 which defines the return trough. Suitably mounted at opposite ends of the side walls 13 are shafts 14 provided with sprocket 30 wheels 15 and 16 over which the endless conveyor chain 17 is trained. The upper run of the chain 17 travels through the upper pan or trough and the lower run through the underlying or lower trough. The end runs travel over the outer 35 peripheral portions of the sprocket wheels 15 and 16. The scraper blade units are denoted and distinguished from one another by the numerals 18. I have taken a marketed or so-called conventional type of scraper blade unit and have revised 40 it to achieve the end herein desired. This unit, as it is now manufactured and used, is in the form of a single casting which is of a length to travel properly and snugly in the channel-way of the associated troughs. The general dimensions are 45 brought out in Figures 2 and 3. The unit is provided, at its center, with what may be called an adapting and attaching chair 19. That is to say, this chair is fashioned to fit down over the centrally arranged endless chain. It includes a horizontal, suitably apertured, flat plate portion 20 and this extends across and fits firmly on the links of chain and the apertures are arranged to accommodate bolts or other fastenings for securing said plate in position. The flat, depending aprons 21 snugly fit against the longitudinal

sides of the chain and provide suitable adjuncts for the outwardly extending blades 22 and 23. The blades are slightly inclined so as to effectively "shovel" and push the coal along through the trough in the direction of the arrow A. All parts of the unit 19 so far described are old in the trade. The only thing that I have done—but this is important—is to fashion the blades, adjacent the chair 18, with scoop-like pocket. The pocket is denoted by the numeral 24 (see Fig. 8), and this is done by shaping up the metal in somewhat a J-shaped form, as indicated at 25. By thus molding and shaping the blade portions, the small scoop-like pockets are formed. It is true that the capacity of these pockets is limited, but the scrapers move rapidly behind one another and therefore each scraper picks up a certain amount of return material and prevents clogging of the intake end of the machine.

In Figure 1, we see the truck B to be loaded with certain overflow of coal or similar material at C. In the operation of the chain and the scrapers, some of the coal finds its way into the lower trough at the point at D. Naturally, as the scraper blades come around, they pick up this material and carry and drag it back from right to left and in a short time there is an obstructive pile of thus returned coal stacked up, as indicated at E. The improved scoop-equipped scraper blades come around and keep lifting off the top of this pile E and pick up a certain proportion thereof and carry it back into the upper trough, to again be carried in the direction of the arrows. The return stroke of the blades is indicated by the arrow F.

In Figure 3 of the drawing, the observer sees the upper run of the endless chain moving away from him in the direction of the arrow A (comparing Figure 3 with Figure 1), and hence sees the convex or trailing sides of the shallow scoop-like pockets. In the same figure, in the lower part, we see the returning scraper units with the recessed sides of the pockets or scoops upside down. They thus return in this upside down state until they sweep around and lift up the surface coal from the pile E, carrying it up from left to right and dumping it back on the platform or partition 11. Here it is retrieved and scraped and carried along until it is discharged out at the right into the truck or car B.

It is thought that persons skilled in the art to which the invention relates will be able to obtain a clear understanding of the invention after considering the description in connection with the drawings. Therefore, a more lengthy description is regarded as unnecessary.

Minor changes in the shape, size and arrangement of details coming within the field of invention claimed may be resorted to in actual practice, if desired.

I claim:

1. In a conveyor construction of the class described, a frame embodying vertical parallel side walls having upper and lower generally horizontal partitions mounted therebetween, said partitions defining upper and lower delivery and return troughs, sprocket wheels mounted at the outer ends of said troughs, an endless sprocket chain trained over said sprocket wheels and having its upper run movable through the upper trough and its lower run movable through the re-

turn lower trough, and a plurality of load-pushing and scraper flights attached at longitudinally spaced points to the runs of said chain, each flight being centrally attached to the chain and having at opposite ends outstanding scraping blades, and said scraping blades being obliquely inclined in respect to the longitudinal axes of said flights to facilitate pushing and discharging the material from the upper trough, and said blades being provided with concavo-convex central portions defining pronounced pockets, and said pockets being adapted to function as loose material-retrieving and returning scoops.

2. As a new article of manufacture, a coal or similar material scraping, pushing, scooping and dumping flight for attachment to and for operable movement by an endless coal conveyor chain comprising a single cast body having a horizontal centrally disposed chain accommodating and attaching portion, said portion being characterized primarily by a flat horizontal plate which is adapted to overlie and to be transversely and rigidly secured on an adjacent run of said conveyor chain, said plate being provided at opposite transverse ends with integral duplicate material pushing and scraping blades, said blades being rectangular in marginal outline and lying in substantially oblique directions in relation to said plate to provide the desired slant for effectively pushing and dumping said material, the major median portions of said blades being transversely concaved to provide scoop-like pockets.

3. As a new article of manufacture, a coal or similar material scraping, pushing, scooping and dumping flight for attachment and for operable movement by an endless coal conveyor chain comprising a single cast body having a horizontal centrally disposed chain accommodating and attaching portion, said portion being characterized primarily by a flat horizontal plate which is adapted to overlie and to be transversely and rigidly secured on an adjacent run of said conveyor chain, said plate being provided at opposite transverse ends with integral duplicate material pushing and scraping blades, said blades being rectangular in marginal outline and lying in substantially oblique directions in relation to said plate to provide the desired slant for effectively pushing and dumping said material, the major median portions of said blades being transversely concaved to provide scoop-like pockets, said pockets being adapted to scoop up loose material and being elongated in lengthwise directions of and occupying the principal area portions of said blades.
